(57) **CLAIM**

The ornamental design for a shot glass, as shown and described.

DESCRIPTION

The file of this patent contains at least one photograph executed in color. Copies of this patent with color photographs will be provided by the Patent and Trademark Office upon request and payment of the necessary fee.

FIG. 1 is a perspective view of a shot glass showing my new design;

FIG. 2 is a front view thereof;

FIG. 3 is a right-side view thereof;

FIG. 4 is a left-side view thereof;

FIG. 5 is a back view thereof;

FIG. 6 is a bottom thereof; and,

FIG. 7 is a top view thereof.

The shot glass has sides that appear to be the top, sides, and bottom of a rattlesnake skin.
